PAINTING INSTRUMENT

Earl M. Barden, Detroit, Mich., assignor to Packard Motor Car Company, Detroit, Mich., a corporation of Michigan

Application July 16, 1930, Serial No. 468,236

2 Claims. (Cl. 91—62.6)

My invention relates to painting instruments and has particular relation to nozzles for striping instruments.

In striping instruments and the like of the type in which a channeled member or nozzle is employed for distributing paint or other liquid on the work surface, difficulty may be encountered in causing the liquid to begin flowing and to flow smoothly and to be evenly distributed. These difficulties may be caused by wear of the portion of the nozzle which contacts with the work surface, or by reason of the construction of the nozzle.

My invention is intended to obviate or greatly reduce these and other difficulties.

An object of my invention is to provide a device for painting certain selected areas of work surface.

Another object of my invention is to provide a paint distributing device in which flow of the paint starts instantaneously with movement of the instrument.

Another object of my invention is to provide a means for distributing the paint after it has reached the work surface and for maintaining a selected thickness and width of stripe.

Another object of my invention is to provide means whereby wear of the nozzle at the point where it contacts the work surface is greatly reduced.

Other objects of my invention will become apparent in the following description of my device taken in connection with the drawing.

Referring to the drawing in which like figures indicate like parts;

Figure 1 is a side elevational view of a striping instrument utilizing one embodiment of my invention;

Fig. 2 is an enlarged view, partly in elevation and partly in section, of the nozzle shown in Fig. 1;

Fig. 3 is a side elevational view of another embodiment of my invention;

Fig. 4 is a side elevational view of another embodiment of my invention;

Fig. 5 is a side elevational view of still another embodiment of my invention; and

Fig. 6 is an end elevational view of the device shown in Fig. 5.

Although my device may be utilized in connection with any device for distributing liquid, it is particularly well adapted for use in connection with a striping instrument such as shown in Fig. 1. The striping instrument includes a body 10 upon which is mounted an upwardly extending

container 11. A projection 12 on the side of the body constitutes a means for pivotally supporting a nozzle 13 and the nozzle is resiliently engaged with the work surface by means of a spring 14. Suitable channels and recesses are provided within the container 11, the body 10, projection 12 and nozzle 13 in order that paint may flow from the container through the instrument and out the nozzle to the work surface (indicated by the dotted line 15). The instrument may be guided in any suitable manner but is preferably guided, at least in part, by the guide roller 16 extending from the side of the body.

The paint is preferably positively fed by means of a gear pump located within the body of the instrument and the pump is adapted to be driven by means of the guide roller 16, whereby movement of the instrument along a work surface, with the guide roller in contact therewith, causes paint to be fed to the nozzle at a rate proportionate to the speed of translation of the instrument causing paint to be delivered to the work surface in a certain predetermined volume per unit of area. The striping instrument itself constitutes no part of my present invention except in its connection with the various nozzles shown, described and claimed.

Referring more particularly to Fig. 2, the nozzle preferably is in the form of a lever arm with an enlarged portion at one end thereof through which a transverse opening 21 has been drilled. The arm is preferably provided with a projecting flange or boss 22 which may be utilized in providing a rest or catch for a spring adapted to cause the arm to resiliently engage the work surface. The arm is preferably provided with a longitudinally extending channel or opening 23 and the lower or contact end of the lever is slightly hooked (24) for better engagement of the nozzle with the work surface. The longitudinally extending channel is preferably slightly enlarged at the lower end to provide a reservoir 25 to hold a small quantity of paint when the instrument is not being moved and paint has stopped flowing through the channel, in order that when the nozzle again moves over the work surface this small quantity of paint is immediately deposited on the work and the action of capillary attraction and surface tension between the work, the paint on the work and the paint in the channels 21 and 23 causes the flow of paint to start instantly.

The materials of the nozzles of the prior art usually were such that the contacting portions thereof wore rapidly thereby quickly destroying the ends of the nozzles and changing the shapes

of the passages therein. As a means of obviating this difficulty a pin 26, of wear resistant material such as high carbon steel, is inserted in a suitably prepared opening in the end of the nozzle 5 so that the pin projects downwardly through and beyond the tip in order that it may contact with the work surface. The pin is frictionally engaged in its opening, so that its position may be adjusted by tapping it up or down. The pin is 10 preferably of a hard, long-wearing material. Since the pin is small and cylindrical and by reason of the abrasive action of the work surface it acquires and maintains a smooth, rounded point particularly suitable for proper engagement 15 of the nozzle with the work surface. The pin is inexpensive and provides a readily adjustable and replaceable work contacting point between the nozzle and the work. In addition, the pin aids in starting the flow of paint since 20 the paint gathers in the pocket or enlargement in the end of the channel and is guided and held by reason of capillary attraction with the pin.

Another embodiment of my invention is shown in Fig. 3 in which the lower end of the channel 23b 25 in the nozzle 13b is enlarged and tapped to provide a threaded recess 27 into which an inverted, cone-shaped tip 28 may be threaded to provide a work contacting portion of the nozzle. The tip is drilled longitudinally to provide a channel for the paint, and is made of a hard, long-wearing material so that the channel is not readily deformed on long continued use of the instrument. The pin, such as shown in Fig. 2, is omitted as 30 the tip itself constitutes the work contacting and paint distributing member.

Another embodiment of my invention is shown in Fig. 4 in which substantially the same nozzle construction shown in Fig. 2 is utilized. The pin 26c, however, is loosely engaged in the openings 35 in the nozzle 13c and is held in place by means of a spring 29 fastened to the side of the nozzle and passing through an opening in the end of the pin. The spring causes the pin to be properly located with reference to the nozzle and provides a resilient coupling between the pin and nozzle. The action of this nozzle is substantially the same as that shown in Figs. 1 and 2 but it is more resilient and the pin requires less adjustment.

Still another embodiment of my invention is shown in Figs. 5 and 6 in which a plurality of pins 26d and springs 28d, such as shown in Fig. 4, are utilized in side by side relation in a lip 30 in a suitable nozzle 13d. By using a plurality of

pins a large opening or pocket is formed in the end of the nozzle, and the pins not only aid in starting the flow of liquid, but also cause the paint to be evenly distributed on the work surface to form a sharply defined line of a certain definite width and of a predetermined thickness. The line so formed is of the same thickness at the side as it is at the center. If desired, a projecting heel 31 may be located on the under side 5 of the nozzle so that the heel engages the work surface to more definitely determine the thickness of the stripe. This heel may be detachably engaged with the nozzle and may be of a hard, wear-resistant material. This nozzle may be used on a curved surface as shown or may be used 10 on a flat surface without readjustment of the nozzle or the pins.

Although I have described certain specific embodiments of my invention I do not wish to be limited thereto as modifications may be made 20 by those skilled in the art without departing from the spirit and scope of my invention as set forth in the appended claims.

What is claimed is:

1. In an instrument for applying stripes, paint 25 applying means comprising a nozzle element pivoted at one end and free at the other end, said nozzle having a paint feeding passage therein with the outlet end terminating in its free end and an opening through the free end coinciding with the outlet end of the passage, and a pin frictionally fitted tightly in the nozzle opening and projecting through the outlet end of the passage to engage and space the outlet end of the passage a predetermined distance from the surface to be 30 striped, said pin being axially adjustable through application of force at either end thereof to vary the distance of its projection beyond the passage outlet.

2. In an instrument for applying stripes, paint 40 applying means comprising a nozzle element having an outlet end formed with a paint feeding passage therein and terminating in an enlarged outlet opening, said nozzle end having a hole formed therein and in communication with the 45 outlet opening, and a pin formed of relatively hard material frictionally retained in the nozzle hole and projecting through the outlet opening, said pin being axially adjustable by the application of force at either of its ends to regulate 50 the space between the outlet opening and the surface to be striped.

EARL M. BARDEEN.
